COMBINED HOOK AND BOLT

Andrew H. Hatchette, Cleveland, Ohio

Application March 21, 1939, Serial No. 263,269

4 Claims. (Cl. 292—105)

This invention aims to provide a novel means whereby a hook may be held securely but releasably engaged with a keeper, it being a matter of common knowledge that a person desiring to crack his way into a house, generally can release a screen door hook from its keeper by shaking or pulling on the door, or by inserting a thin, hook-lifting instrument between the door and the door frame.

Fig. 1 is an elevation wherein the bolt is retracted, Fig. 2 is an elevation wherein the bolt is advanced, Fig. 3 is an elevation showing a modification, the bolt being advanced, and Fig. 4 is an enlarged elevation of the spiral body of the hook, the showing of Fig. 4 applying to either form of the invention.

The numeral 1 marks either a door or door jamb, carrying a screw-eye or other keeper 2. The numeral 3 designates a hook, made of a piece of rigid rod stock of common cross sectional diameter throughout its length, the hook including a longitudinal shank 4 having at one end an eye 5 whereby the hook is pivotally connected to a screw eye or other anchor 6, adapted to be mounted on either a door frame or a door. The bill 7 of the hook 3 extends through the keeper 2 and has a side seat 8.

The intermediate portion of the shank 4 is formed into a spiral body 9, the terminal convolutions 10 of which are closer together than are the remaining or intermediate convolutions. A bolt 11 is closely guided for right line reciprocation in the body 9 but is rotatable therein, the bolt having a lateral handle 12, movable between, and adapted to follow, the convolutions of the body.

The operator lays hold of the handle 12 and rotates the bolt 11, the handle follows the convolutions of the body 9, the bolt is advanced, the working end of the bolt cooperates with the seat 8, and the bill 7 of the hook cannot be disengaged from the keeper 2. When the handle 12 reaches the less widely spaced convolutions 10 at the forward end of the body 9, it is pinched between them, and it will not be possible, by shaking the door, to cause the handle 12 to swing down, follow the convolutions of the body 9 and retract the bolt 11 out of engagement with the seat 8. The less widely spaced convolutions 10 at the rear end of the body 9 function in the same way, to hold the bolt 11 retracted.

In Fig. 3, parts hereinbefore described have been designated by numerals already used, with the suffix *a*. The body 9a is shorter than the

body 9, and the bolt 11a has a shorter throw than the bolt 11. Added security and stability in the bolt 11a are secured by mounting it in a depending guiding eye 14, produced by looping and twisting the shank 4a on itself, the guiding eye being disposed close to the bill 7a. Security is promoted, moreover, because the working end of the bolt 11a engages not only with the seat 8a, but underneath and in contact with the keeper 2a, as well.

A smith or iron-master, who abides by what is claimed, may make changes in the precise structures shown, without departing in corresponding measure from the spirit of the invention.

I claim:

1. A two-piece retainer for screen doors and similar closures, including a hook formed from rod stock and comprising a shank having a bill, the shank being spirally disposed to form a body, and a bolt mounted in the body, for longitudinal movement and for rotation, the bolt having a transverse handle, extended outwardly between the convolutions of the body and exposed there beyond for direct manipulation, the handle constituting means whereby the bolt may be rotated, the handle following the convolutions, when the bolt is rotated, thereby to advance the bolt longitudinally, into cooperating relation with respect to the bill.

2. A two-piece retainer for screen doors and similar closures, constructed as set forth in claim 1, and wherein the convolutions at one end of the body are located more closely together than are the other convolutions, and so closely together as to pinch the handle and hold the bolt releasably against rotation and longitudinal movement.

3. A two-piece retainer for screen doors and similar closures, constructed as set forth in claim 1, and wherein the convolutions which are at the inner end of the body are located more closely together than are the other convolutions, and so closely together as to pinch the handle and hold the bolt releasably against rotation and longitudinal movement out of cooperating relation with respect to the bill.

4. A two-piece retainer for screen doors and similar closures, constructed as set forth in claim 1, and wherein the shank is distorted upon itself to form a guiding-eye, spaced from the body and close to the bill, the bolt being slidable in the guiding-eye.

ANDREW H. HATCHETTE.
